UNITED STATES PATENT OFFICE.

AMOS O. PAYNE, OF WICHITA, KANSAS.

FILLER SPOUT.

Application filed January 8, 1926. Serial No. 79,911.

This invention relates to filler spouts of that general class used to deliver liquid to receptacles such for example as tanks, cans and the like.

5 In my U. S. Patent Number 1,550,738, August 25, 1925, I have shown a construction of filler spout which will cut off the flow of liquid when the liquid reaches a predetermined level but in that construction there is an operating handle manually operated to unseat a valve. The handle in the patented structure may accidentally press against the ground or against some object so as to cause it to unseat the valve at an inopportune time so 15 liquid flow will be permitted when it is not desired.

My present invention contemplates a structure in which it will be impossible to accidentally unseat the valve and to this end it 20 comprehends a manually controlled means independent of the operating mechanism for rendering the valve-unseating mechanism functional only so long as the means just mentioned is held in functional position but 25 there is means also provided for automatically cutting off the flow of liquid when the lever in the tank or receptacle reaches a predetermined level or becomes full.

The novel construction by means of which 30 the desired result is accomplished will be clearly understood by reference to the following description in connection with the accompanying drawings in which:

Figure 1 is a vertical longitudinal sectional view of a filler spout constructed in accordance with my invention, part of the nozzle being removed.

Figure 2 is a fragmentary perspective view of the positively actuated operating 40 mechanism, and;

Figure 3 is a fragmentary sectional view of the nozzle.

1 designates the tubular end of the filler spout to which the hose from the source of supply is attached. 2 designates a nozzle connected to the tubular member by an intermediate housing or casing 3 in which may be located the valve operating and controlling mechanism which includes the novelty of my 45 invention.

At the juncture of the tubular member with the housing is a valve seat 4 having a forwardly directed valve stem guide 5 in which is a valve stem 6 having a valve 7 at one end and a fixed collar 8 at the other. A coil spring 9 surrounds the guide one end of which bears

against the collar 8 tending to keep the valve seated to close off the flow of liquid.

The end of the stem distant from the valve 7 is pivoted to a connector 10 having a slot 11 in which the extremity of the stem 6 is received and pivoted at 12. A link 13 is pivoted to the connector or bar 10 at 14 and it is also pivoted to a finger 15 at 16, the finger 15 being fast to a shaft 17 mounted in the casing and having at least one end projecting through the casing to support a hand lever 18 extending to the tubular portion 1 so that it can be easily grasped by the hand of the operator. The connector 10 and the link 13 constitute a break joint which is normally held in functional position by the spring 19 coiled at its center about the pivot 14 which connects the link 13 to the connector 10, the ends of the spring bearing against the pivots 12 and 16. It should be here noted that the pivot 14 should be slightly offset below the pivots 12 and 16 so as to most efficiently hold the parts 6, 10 and 16 in the functional positions shown in the drawings so that when the handle 21 is pressed downward the shaft 17 will be rocked to swing the finger 15 to force the valve off its seat.

Normally the break joint is held out of functional position to operate the valve 7 by 55 the pin 22 in guide 23 carried by the case 3. The pin 22 is pivoted to the end 24 of the lever 25 fulcrumed to the lug 26 and normally pressed outwardly by the expansion spring 27 bearing against the housing 3 and the lever 25. Since the spring is on that side of the fulcrum distant from the pin, it will be apparent that the normal tendency will be for the spring to force the handle 25 out and the pin 22 in so as to exert a push against the 60 plate 28 integral with connector 10 to force the pivot 14 above the pivots 12 and 16 and while the parts are in this position the joint will be broken or rendered non-functional to 65 unseat the valve 7 so that even when the handle 21 is pressed in the valve 7 will not be unseated unless the handle 29 on lever 25 is at the same time pressed in to withdraw the pin 22 from engagement with the break-joint. Of course the practical way will be 70 to place the handles 21 and 29 in substantially the positions so that they can be grasped simultaneously with the same hand. The parts are therefore so disposed that one lever (25), must be in position to permit 75 spring 27 to urge pin 22 upwardly to contact with the joint consisting of the levers 11 and 80

12 so that the lever 18 will not be effective to open the valve 7. When, however, the handle 29 is moved toward the member 1 to compress the spring 27, the spring 19 will cause the links of the joint to align so that the lever 18 may become effective to unseat the valve 7.

There is another feature of importance in this device which is generically disclosed in my former patent but slightly modified to suit this latest form of my invention.

The feature just referred to is the provision of automatic means to cause the valve 7 to seat when the liquid in the receptacle being filled, reaches a predetermined level 15 which is generally when the tank is full.

The automatic cutoff includes a sealed diaphragm chamber 30 having a rigid wall 31 and a flexible wall or diaphragm 32, the chamber having an opening 34 communicating 20 with a tube 35 passing through the wall of a Venturi tube 36 in the nozzle 2, terminating at the discharge end of the nozzle.

The diaphragm 32 carries a stud 37 pivoted to a lever 38 fulcrumed on the stud 39, 25 carrying at its free end a link 40 engaging the slot 41 in the plate 28.

The automatic cutoff operates as follows: When the liquid is flowing through the nozzle and particularly through the Venturi tube 30 the velocity of the liquid will tend to exhaust the air out of the chamber 30 through opening 42 but since the lower end 43 of the pipe 35 is open to atmosphere maintaining a constant atmospheric pressure at the inlet end 43 35 of pipe 42, air will be drawn up through end 43 to outlet opening 42 this being the easier path for the air to travel because when the pressure in the chamber 30 drops slightly below atmospheric pressure there will be a 40 tendency to reestablish the pressure in said chamber, while a drop in pressure at the outlet 42 will cause air to rush into the tube 35 through the inlet 43. When, however, the lower end 43 of the pipe 35 is submerged the end 43 will be thus sealed, it will then be easier to exhaust air from chamber 30 than to lift the liquid in pipe 35. As a result, a 45 partial vacuum will be established in chamber 30 so that a down pull will be exerted 50 upon the stud 37 and an up pull on the rod 40 to swing the connector 10 about the pivot 12.

This will raise the pivot 14 in a plane above pivots 12 and 16. The relatively strong 55 spring 9 may now become effective to snap the valve 7 upon its seat by causing the break joint to buckle.

This latter action will take place even when the two handles 21 and 29 are close to the 60 tubular portion 1, consequently the valve will be automatically seated whenever the discharge end of the nozzle is submerged and the liquid is flowing from the source of supply.

65 From the foregoing it will be seen that

danger of accidental undesirable unseating of the valve will be entirely prevented and closing of the valve will be assured when the predetermined level in the receptacle has been reached.

What I claim is:

1. A filler spout comprising a tubular casing having a valve seat, a valve, a spring for normally maintaining said valve on its seat, an actuator for unseating the valve against the action of the spring, a break joint connecting the actuator to the valve, and manually controlled means carried by the casing for breaking the joint to render the actuator ineffective to unseat the valve.

2. A filler spout comprising a tubular casing having a valve seat, a valve, a spring for normally maintaining the valve on its seat, a shaft in the casing, an actuating lever connected to the shaft outside the casing, an actuating lever connected to the shaft inside the casing, a toggle joint between the actuating lever and the valve, a spring normally urging the links of the toggle joint in alignment, a lever pivoted to the casing, a pin projecting into the casing connected to the lever, a spring normally urging the lever to a position to cause the pin to contact with the toggle joint to break it, and a handle on the last named lever against which pressure can be exerted to compress the last named spring to permit the last named lever to draw the pin away from the toggle joint.

3. A filler spout comprising a tubular casing having a valve seat, a valve, a spring for normally maintaining the valve on its seat, a shaft in the casing, an actuating lever connected to the shaft outside the casing, an actuating lever connected to the shaft inside the casing, a toggle joint between the actuating lever and the valve, a spring normally urging the links of the toggle joint in alignment, a lever pivoted to the casing, a pin projecting into the casing connected to the lever, a spring normally urging the lever to a position to cause the pin to contact with the toggle joint to break it, a handle on the last named lever against which pressure can be exerted to compress the last named spring to permit the last named lever to draw the pin away from the toggle joint, a closed chamber above the tubular casing, a diaphragm in the chamber, a lever connected to the diaphragm, a rod connected to the lever and toggle joint respectively, and a tube communicating the chamber on one side of the diaphragm with atmosphere.

4. A filling spout comprising a tubular casing having a valve seat, a valve, means for urging the valve into seating position, an actuating lever to unseat the valve, a toggle joint consisting of pivoted links connecting the actuating lever to the valve, means tending to hold the links of the toggle joint in alignment so that unseating movement may

be communicated to the valve from the lever, and a manually actuated pin for breaking the joint between the actuating lever and the valve formed by the toggle joint so that movement of the actuating lever will be ineffective to unseat the valve.

5. A filling spout comprising a tubular casing having a valve seat, a valve, means for normally urging the valve into seating position, an actuating lever for unseating the valve, a toggle joint comprising two pivoted links connecting the actuating lever to the valve, a spring normally tending to hold the links of the toggle joint in alinement, and a 10 spring-pressed pin normally urged into position to break the toggle joint to render the actuating lever ineffective to unseat the valve.

6. A filling spout comprising a tubular casing having a valve seat, a valve, means normally urging the valve toward seating position, a rock shaft, a hand operated lever outside the casing on one end of the rock shaft, a valve actuating lever inside the lever connected to the rock shaft, a toggle joint connecting the actuating lever and the valve, means for holding the toggle joint rigid, a spring-pressed lever carried by but outside the casing, and a pin connected to the last named lever extending into the casing to contact with the toggle joint to break the joint so that the actuating lever will be ineffective to unseat the valve.

15 In testimony whereof I affix my signature.

AMOS O. PAYNE.
